(57) **CLAIM**

The ornamental design for a photo frame, as shown and described.

DESCRIPTION

FIG. 1 is a top, front and right side perspective view of a photo frame showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom, rear and left side perspective view thereof;

FIG. 9 is an exploded, top, front and right side view of the photo frame; and,

FIG. 10 is an exploded, bottom, rear and right side view, thereof.

The broken lines show the features of the photo frame that form no part of the claimed design.

1 Claim, 10 Drawing Sheets
